ALBERT H. DE VOE, OF WESTFIELD, NEW JERSEY, ASSIGNOR TO THE SINGER MANUFACTURING COMPANY, A CORPORATION OF NEW JERSEY.

RUFFLING MECHANISM FOR SEWING-MACHINES.

1,240,956.

Specification of Letters Patent. Patented Sept. 25, 1917.

Application filed December 19, 1913. Serial No. 807,571.

To all whom it may concern:

Be it known that I, ALBERT H. DE VOE, a citizen of the United States, residing at Westfield, in the county of Union and State 5 of New Jersey, have invented certain new and useful Improvements in Ruffling Mechanism for Sewing-Machines, of which the following is a specification, reference being had therein to the accompanying drawings.

10 This invention relates to improvements in ruffling mechanism for sewing machines, and it has for its object to provide simple, effective and readily adjustable means, so arranged with respect to the sewing ma-

15 chine frame that the parts, with the exception of the ruffling blade, remain elevated above the work-plate and offer no obstruction to the work.

The improvements comprise a ruffling 20 lever provided with a longitudinally disposed thrust-rod which enters an aperture formed in an oscillatory fulcrum stud journaled in the head of the overhanging bracket arm of the sewing machine. Surrounding 25 said thrust-rod between the fulcrum stud and a collar fixed to the rod is a pressure spring which acts upon the ruffling lever to press the same bodily downward. At its lower end the ruffling lever is formed with 30 spaced arms, one of said arms extending below the other and having fixed thereon the shank of a ruffling blade. It will be seen that the yielding ruffling lever is adapted for vibratory movement with its fulcrum stud 35 and for endwise movement relatively thereto. Operative movements are imparted to the ruffling lever by means of a rock-arm comprising two sections or plates which embrace the spaced arms of the lever, said arms 40 receiving between them a friction roller upon the end of a coupling stud connected to the rock-arm and adjustable within a slot formed in the outer section of the same. The rock-arm is connected to the end of a 45 rock-shaft mounted in fixed bearings within the head of the overhanging bracket-arm and provided with a crank arm having a forked extremity which embraces a slide block upon a crank-disk carried by the needle actuating rock-shaft which is operatively connected to the driving shaft of the 50 machine.

In the drawings, Figure 1 is a front elevation of a sewing machine embodying the 55 present improvements, and Fig. 2 is a side

elevation of the same, partly in section. Fig. 3 is a detail view of the actuating members for the rock-arm, and Fig. 4 is a side elevation of the same, partly in section. Fig. 5 is a sectional view of the rock-arm 60 from the underside thereof, showing its connections with the ruffling lever.

The present improvements are shown embodied in a sewing machine formed with the overhanging bracket arm A provided with 65 the head 1 in which is journaled a vertically reciprocating needle-bar 2 carrying the needles 3 arranged in a plane at an angle to the line of feed. The machine is provided with a presser-bar 4 to the lower end of which is 70 connected by means of screw 5 the shank 6 of a pivotally attached presser-foot 7. Journaled within a bearing formed in the upper portion of the head 1 is a fulcrum stud 8 provided with the enlarged head 9 75 which, in conjunction with nut 10 at the opposite end of the stud serves to hold the same against longitudinal movement. The head 9 of the fulcrum stud is provided with a transverse aperture to receive a thrust-rod 80 11 carried by a ruffling lever 12.

The ruffling lever 12 is provided at its upper end with a lateral arm 13 secured in fixed position upon the lever by means of screws 14 and formed with a transverse 85 aperture to receive the thrust-rod 11 which is secured in fixed position within arm 13 by means of screw 15. The lower end of thrust-rod 11 enters an aperture formed in an arm 16 secured in fixed position upon the 90 ruffling lever by means of a screw 17 and carrying a projecting stud 18 having an enlarged head which forms a finger piece by which the ruffling lever may be raised or lowered. Surrounding the thrust-rod be- 95 tween the fulcrum stud 9 and a collar 11 upon the rod, is a pressure spring s which acts upon the ruffling lever to press the same bodily downward.

The ruffling lever is provided with de- 100 pending spaced arms 19 and 20, arm 20 extending below arm 19 and being provided with a seat to receive the shank 21 of a ruffling blade 22 which is secured to the lever by means of screws 23 and 24.

The actuating mechanism for the ruffling lever comprises a rock-arm formed in two sections or plates 25 and 26 which embrace the arms 19 and 20 of the lever. The plate 25 is disposed adjacent the face of head 1 110

and is fixed upon the end of a rock-shaft 27 journaled in a fixed bearing 28 mounted within and transversely of the head 1. The plate 26 upon its inner face is provided with 5 a lateral projection 29 which forms a seat to which is secured by means of screws 30 the inner section or plate 25 of the rock-arm. The rock-arm is provided with a slot or 10 guide-way 31 which is formed in and longitudinally of an extension 26^x of plate 26 disposed transversely of plate 25, said guide-way 31 being so arranged that its sides become substantially parallel with arms 19 and 20 of the ruffling lever at the end of a 15 ruffling stroke. At one side of the guide-way 31 the extension 26^x of the rock-arm is provided with a series of graduations 32 to form a scale over which lies a thumb-nut 33 upon the end of a coupling stud 34 having 20 its enlarged head formed with rectangular faces 35 which abut the side walls of guide-way 31, and which merge into a flange 36 which lies within a channel formed in the rear face of extension 26^x to receive a friction roller 37 carried by stud 34 and extending 25 between arms 19 and 20 of the ruffling lever whereby the same is operatively and adjustably connected with the rock-arm.

It will be seen that the position of the 30 coupling stud 34 and the corresponding stroke of the ruffler blade under the vibratory movements of the rock-arm are indicated by the thumb-nut 33 in connection with the scale 32, which latter is in practice provided with suitable numbers representing 35 the range of movement of the ruffler blade. The rock-shaft 27 by which operative movements are imparted to the rock-arm is fitted within the hub 38 of a crank-arm 39 40 and is secured thereto by means of screw 40. The crank-arm 39 is provided with a forked extremity 39^x which embraces a slide-block 41 pivotally mounted upon a stud bolt 42 carried by crank disk 43 fixed upon the end 45 of the needle actuating rock-shaft 44 journaled in and lengthwise of the overhanging bracket-arm A.

The presser-bar 4 is raised to elevate the 50 presser-foot 7 above the work by means of the usual lever 45. The presser-foot shank carries a lateral arm 46 which, in its upward movement, comes into contact with the projecting end of screw 23 and bodily lifts the ruffling lever to which said screw is connected, whereby the ruffler blade 22 is elevated above the work-plate W and ruffling plate P. The work is then placed under the presser-foot and the latter is lowered upon the same, its downward movement permitting the spring s of the ruffling lever to 55 return the lever to its effective position and the blade 22 in operative engagement with the work. The operation of the ruffling mechanism in conjunction with the stitch-forming and feeding mechanism, which may

be of any suitable construction, is similar to that of other machines of the present class, the ruffling blade being advanced to produce a fold in the work beneath the presser-foot during the rise of the needles and being returned to initial retracted position during the descent of the needles into the fold thus produced. It will be seen that the endwise movable spring-yielding ruffling lever permits the use of a ruffling blade of strong and rigid construction, inasmuch as the blade is maintained in fixed relation to the ruffling lever throughout the movement of the latter. It will also be noted that at the beginning of a ruffling stroke the ruffling lever is inclined toward the direction of feed, its fulcrum being disposed at the rear of the needle-bar, and that such arrangement results in a constantly increasing spring pressure upon the lever and its blade as the latter is moved forwardly and approaches a vertical line drawn through the axis of the fulcrum-stud 9; and vice versa the degree of pressure upon the ruffling blade constantly decreases as the blade is returned to initial position.

It will be understood that the improvements are susceptible of various modifications in construction and arrangement of parts from the embodiment herein shown and described without departure from the scope of the invention.

Having thus set forth the nature of the invention, what I claim herein is:—

1. In a sewing machine, the combination with stitch-forming mechanism including a reciprocating needle and feeding mechanism, of ruffling mechanism including a vibratory ruffling lever and a fulcrum therefor with respect to which said lever is endwise movable, a rigid ruffling blade carried by said lever, said fulcrum and blade being disposed on opposite sides of the needle-path, a spring acting upon said lever to press said blade into operative relation with the work, a rock-arm and adjustable means for transmitting to-and-fro movements from the rock-arm to said lever.

2. In a sewing machine, the combination with stitch-forming mechanism and feeding mechanism, of ruffling mechanism comprising a vibratory ruffling lever, a fulcrum-stud therefor, a thrust-rod carried by said ruffling lever and entering an aperture in said fulcrum-stud, a pressure spring surrounding said thrust-rod, a ruffling blade carried by said lever, actuating means for said lever including a rock-arm, and means for adjustably connecting said rock-arm and the lever.

3. In a sewing machine, the combination with stitch-forming mechanism and feeding mechanism, of ruffling mechanism comprising a vibratory ruffling lever, an oscillatory fulcrum-stud with which said lever is con-

nected for endwise movement relatively thereto, a ruffling blade carried by said lever, a pressure spring acting upon said lever to press the blade upon the work, a rock-arm having opposed faces which embrace the lever, actuating means for said rock-arm, and means for adjustably connecting said rock-arm and the lever.

4. In a sewing machine, the combination 10 with stitch-forming mechanism and feeding mechanism, of ruffling mechanism comprising a vibratory ruffling lever, an oscillatory fulcrum-stud with which said lever is connected for endwise movement relatively 15 thereto, a ruffling blade carried by said lever, a pressure spring acting upon said lever to press the blade upon the work, a rock-arm having opposed faces which embrace the lever, means for adjustably connecting said 20 rock-arm and the lever, and actuating means for said rock-arm including a rock shaft, a crank-disk, a slide-block upon said disk, and a crank-arm connected to said rock-arm and having a forked end embracing said 25 slide-block.

5. In a sewing machine, the combination with stitch-forming mechanism and feeding mechanism, of ruffling mechanism comprising a vibratory and endwise movable ruffling 30 lever and a fixed fulcrum therefor, a ruffling blade carried by said lever, a pressure spring acting upon said lever to press the blade in operative relation with the work, a longitudinal guideway formed in said lever, a 35 rock-arm comprising two rigidly connected plates intermediate which said ruffling lever is received, one of said plates being provided with a guide-way, a coupling member for the ruffling lever and rock-arm and adjustable within said guide-ways, a rock-shaft 40 fixed to said arm and provided with a crank-arm, an actuating rock-shaft, and operative connections between said actuating rock-shaft and the crank-arm.

45 6. In a sewing machine, the combination with stitch-forming mechanism and feeding mechanism, of ruffling mechanism including a vibratory ruffling lever and a fulcrum therefor with respect to which said lever is 50 endwise movable, spaced arms carried by

said lever, a ruffling blade connected to one of said arms, a rock-arm comprising two rigidly connected plates intermediate which the arms of the ruffling lever are received, one of said plates being formed with a longitudinal channel and with a guideway intersecting said channel, a coupling-stud provided with opposed rectangular faces which abut the side walls of said guide-way and carrying a roller-stud received within said 60 channel and projecting between the spaced arms of the ruffling lever, and actuating means for said rock-arm.

7. In a sewing machine, the combination 65 with a frame, stitch-forming mechanism, and feeding mechanism, of ruffling mechanism including a vibratory ruffling lever, a ruffling blade rigidly secured to and forming a fixed part of said lever, a rock-arm extending in the same general direction as said 70 ruffling lever and mounted adjacent thereto, and a connection between said rock-arm and ruffling lever adjustable lengthwise of these parts through which the lever is positively vibrated by the rock-arm and by means of 75 which the length of such vibrations may be changed.

8. In a sewing machine, the combination 80 with a frame, stitch-forming mechanism including a reciprocating needle, and feeding mechanism, of ruffling mechanism, comprising a vibratory ruffling lever, a rigid ruffling blade secured upon and in fixed relation to said lever, a fulcrum for said lever secured to a stationary part of the frame and disposed at the side of the needle-path opposite 85 said blade, a spring acting upon said lever to press the blade into operative relation with the work and actuating means connected with said lever and adapted to move 90 the same to carry the blade toward the needle-path.

In testimony whereof, I have signed my name to this specification, in the presence of two subscribing witnesses.

ALBERT H. DE VOE.
